UNITED STATES PATENT OFFICE

NATHANIEL E. LOOMIS, OF ELIZABETH, NEW JERSEY, ASSIGNOR TO STANDARD OIL DEVELOPMENT COMPANY, A CORPORATION OF DELAWARE

CONVERTING HYDROCARBON

Application filed May 5, 1924. Serial No. 711,138.

This invention relates to the art of converting hydrocarbons into lower boiling products, and will be understood from the following description, reference being had 5 also to the accompanying drawing which represents in front elevation one form of apparatus contemplated.

In the drawing the numeral 1 designates a pressure still mounted in a suitable heating furnace. The vapor pipe from the still leads into a reflux condenser, for instance an air-cooled coil 2, and thence to a final condenser 3 and receiver 4. From the intermediate portion of the reflux condenser, a 10 condensate trap-out connection 5 leads to a collector tank 6 provided with a draw-off pipe 7 and a connection 8 to a pump 9. The pump 9 is in feed relation to a cracking coil 10 mounted in a suitable furnace and 15 having, if desired, a drum 11 guarded against heat loss in any preferred manner. An off-take pipe 12 leads the cracked products to a vapor separator 13 having a drain pipe 14 and a pipe 15 for draw-off of intermediate condensate. A vapor off-take 20 pipe 16 from the separator 13 leads to a final condenser 17 and receiver 18.

In operation, a hydrocarbon stock to be cracked, for example a gas oil, is supplied 25 to the pressure still 1, as through line 20, and a cracking temperature being maintained, vapors pass under a pressure of for instance 95-100 lbs. gauge (as maintained by valve 19 etc.) to the partial condensing zone 25 in the reflux condenser. Heavy condensate formed in the lower part of the reflux condenser returns to the still, but the condensate forming in the upper part of the reflux condenser is of lighter character, and this is 40 trapped out by connection 5, while the uncondensed vapors pass on to the final condenser 3. The trapped out condensate thus diverted may be taken off by pipe 7 for any 45 use desired, or it may be taken off by connection 8 and forwarded by pump 9 to the cracking coil 10 where it is subjected to a cracking temperature under higher pressure. Products from the cracking coil or 50 drum pass to the vapor separator 13 and

vapors from thence proceed to the final condenser 17.

If all of the condensate produced in the reflux condenser were diverted from the still, such procedure would impose a needless and heavy burden upon the still in heating the correspondingly increased amount of fresh feed stock required to compensate, and I accordingly separate out only the lighter portion of the reflux which is most 55 unsuited to pressure still treatment and allow the heavier portion to return for further cracking.

I claim:

1. Apparatus of the character described, 65 which comprises a still, a reflux condenser for receiving vapors therefrom, means for retaining pressure upon the vapors in the still and reflux condenser, a trap-out connection in the intermediate portion of said 70 reflux condenser, a cracking coil for receiving trapped-out condensate and adapted to operate at higher pressure than the still, a vapor separator in connection with said cracking coil and a condenser in connection 75 with said vapor separator.

2. Apparatus of the character described, 80 which comprises a pressure still, a reflux condenser for receiving vapors therefrom, a trap-out connection in the reflux condenser 80 for diverting a lighter fraction of condensate formed, a cracking coil joined with said trap-out connection and adapted to operate at higher pressure than the still, and a drum 85 guarded against heat loss and connected to receive effluent from the cracking coil.

NATHANIEL E. LOOMIS.
